UNITED STATES PATENT OFFICE.

LEWIS J. INGRAM, OF ANGUS, TEXAS.

HAMES-FASTENER.

1,204,774.

Specification of Letters Patent. Patented Nov. 14, 1916.

Application filed May 9, 1916. Serial No. 96,376.

To all whom it may concern:

Be it known that I, LEWIS J. INGRAM, a citizen of the United States, residing at Angus, in the county of Navarro and State 5 of Texas, have invented new and useful Improvements in Hames-Fasteners, of which the following is a specification.

The invention relates to hames fasteners, and more particularly to the class of strap 10 fasteners for hames.

The primary object of the invention is the provision of a fastener of this character wherein the hames string can be adjusted on the hames so that the latter will 15 snugly fit the horse collar and when such strap is adjusted the same will be securely fastened to hold the hames tightly upon the collar.

Another object of the invention is the 20 provision of a hames strap fastener of this character wherein the same is mounted upon the hames and will permit the easy adjustment of the hames strap with despatch and will securely hold the hames upon the horse 25 collar.

A further object of the invention is the 30 provision of a hames strap fastener of this character wherein the construction thereof is novel in form to assure the tight and firm fastening of the hames strap and also to permit a wide range of adjustment therefor of the fastening of the hames about different sizes of horse collars.

A still further object of the invention is 35 the provision of a fastener of this character which is simple in construction, thoroughly reliable and efficient in operation, strong, durable and inexpensive in manufacture.

Other objects will be in part obvious and 40 in part hereinafter set forth.

The invention accordingly consists in the 45 features of construction, combination of elements and arrangement of parts which will be exemplified in the construction herein- 50 after described, and the scope of the application of which will be indicated in the appended claims.

In the accompanying drawings: Figure 55 1 is a front elevation of a pair of hames and the hames strap, showing the fasteners constructed in accordance with the invention upon the hames; Fig. 2 is an edge elevation thereof; Fig. 3 is a sectional view on the line 3—3 of Fig. 1; Fig. 4 is a sec-

tional view on the line 4—4 of Fig. 2; Fig. 55 5 is a sectional view on the line 5—5 of Fig. 1.

Similar reference characters indicate corresponding parts throughout the several views in the drawing. 60

Referring to the drawing in detail, A designates each hame, which is of the usual contour, and these hames are adapted to be adjustably and detachably fastened about a horse collar through the medium of a hame 65 strap B in the usual well known manner. Secured to the outer edge of each hame A is a metallic reinforcing strip 5, while formed in opposite edges of the said strip 5 near the upper end thereof are notches 6 70 in which is engaged a bearing strap 7. Swingly supported upon a pivot 8 there- 75 in is a keeper 9 formed with a series of alternately arranged notches and teeth 10 and 11, while arranged within a suitable recess 12 formed in the hame A next to the strip 5 is a latch 13 which is supported upon a pivot 14 and is acted upon by a coiled expansion spring 15 within the recess 12 so 80 as to normally hold the latch 13 in position for locking engagement with a hook 16 formed on the tooth 11 at the outermost end of the keeper 9 to lock the same in closed position so as to engage with the strap B when about the hames A for the fas- 85 tening of the latter upon a horse collar.

In the front face of the hame A is a notch 17 which permits access to be had to the end adjacent thereto of the latch 13 so that the finger can be engaged with the latch for 90 swinging the same to releasing position against the action of the spring 15 for the freeing of the keeper 9 so as to permit the adjustment of the hames strap B upon the hames and the fastening of the strap by the 95 keeper 9 when closed and locked by the latch 13 engaging therewith.

The engagement of the bearing strap 7 in the notches 6 in the strip 5 prevents displacement of the said bearing on the strip, 100 said strip 5 being fastened upon the hame in any suitable manner.

From the foregoing description, taken in connection with the accompanying drawing, the construction and manner of use of the 105 herein described hames fastener will be readily understood and, therefore, a more extended explanation has been omitted.

Having thus described my invention, I claim:

The combination with a hame and a hame strap adapted to be engaged with said hame, of a bearing strap on the hame, a reinforcing strip secured to the hame and having notches in opposite edges for receiving the bearing strap, a keeper pivotally supported in the bearing strap and adapted to adjust-

ably receive the hame strap, and a spring-held latch pivoted in the hame and engageable with the keeper to lock the same closed.

In testimony whereof I affix my signature in presence of two witnesses.

LEWIS J. INGRAM.
